UNITED STATES PATENT OFFICE.

ALLEN C. ALLAN, OF CHICAGO, ILLINOIS.

PLIERS, WRENCH, AND THE LIKE.

1,337,986.

Specification of Letters Patent. Patented Apr. 27, 1920.

Application filed May 19, 1919. Serial No. 298,112.

To all whom it may concern:

Be it known that I, ALLEN C. ALLAN, a citizen of the United States, residing at Chicago, in the county of Cook and State of Illinois, have invented certain new and useful Improvements in Pliers, Wrenches, and the like, of which the following is a specification.

My invention relates to a new and improved style of pliers, wrenches, and similar tools, adapted for use with articles of various sizes and shapes and particularly designed for quick and proper application thereto, the novel devices being what might 10 be termed semi-automatic in that their constructions greatly assist in their rapid and accurate association with the body to be grasped. A further feature of the invention is the provision of an appliance of this type 15 having a large range or degree of opening between its jaws, thus adapting it to bodies of greatly differing dimensions without unduly changing the position of the handle elements leaving them always in proper and 20 suitable relation for grasping with the hand.

Thus there is provided an adjustable tool 25 having work-engaging jaws variable in their degree or extent of separation with a retention of the handles in much the same angular position or separation apart throughout the extent of adjustment of the jaws.

An additional object of the invention is the production of a device of this character composed of few and simple parts, which 35 will firmly and securely grip bodies of different dimensions or sizes, which is strong and unlikely to be broken in service, and which can be properly and quickly applied to the body to be turned, the shape of the 40 tool or appliance facilitating this action.

In order that those trained in this art 45 may have a full and complete understanding of the invention, both from structural and functional standpoints, I have illustrated a desirable and preferred embodiment of the invention in the accompanying drawing forming a part of this specification and to which reference should be had in connection with the following detailed description.

In this drawing the single figure shows a face view of the improved and novel tool.

Referring to the drawing, it will be perceived that the tool or appliance comprises 55 merely two associated or crossed levers 10 and 11, the former being slotted at 12 for

the extension of the latter therethrough. The lower portion of lever 10 is curved at 13 to form a handle of convenient shape, and the upper end 14 extends laterally at substantially right-angles to the length of the main body of the lever, being provided at one side of its end with a flat or plain working surface or jaw face 15 which may be roughened in the customary way, if desired. As is fully shown, the curved edge portion 16 at the inner face of the bend in the arm is equipped with teeth to form one element of a pipe-wrench. The companion lever or arm 11 has a curved handle section 17 and a thickened end jaw portion 18 with a flat work-engaging face 19 adapted to bear against the face of the body to be held directly opposite the face engaged by the surface 15 of the companion jaw. Thus, the 70 two faces 15 and 19 are designed to be parallel when in coöperative working relation, as shown. As is clearly illustrated, the inner edge of the upper portion of the member 11 is curved or recessed at 20 and 75 provided with sharp teeth, whereby this portion of the arm or lever may be used as a coöperating or companion pipe-wrench element with the part 16, all as will be 80 readily understood.

One purpose of the invention is the provision of an automatically-adjustable fulcrum between the levers, whereby the jaws may correctly grip bodies of different sizes with their work-engaging faces 15 and 19 85 always parallel or their curved pipe-wrench surfaces in proper coöperative relation and their handle portions a suitable distance apart for easy and effective grasping. The corner 21 of the lower end wall of the slot 90 12 constitutes one of the fulcrum elements and the edge 22 of the lever 11 is so shaped or curved that for all sizes of nuts, bolts, and the like between the jaws, with the face 19 parallel to the surface 15, or with different sizes of pipes grasped by the pipe-wrench part of the tool, the two elements 95 21 and 22 will be in contact or bearing relation. It will be clear, therefore, that the effective fulcrum automatically shifts or 100 changes position to maintain the parts in the desired correlation with the handle elements 13 and 17 a suitable and convenient distance apart for efficient action. Total separation of the two members is prevented 105 by the thicker handle portion 17 and the jaw 18 of increased thickness, neither of which 110

arts can pass through the slot 12. In manufacturing the appliance the member 10 is drop-forged with the side-walls of the slot 12 separated sufficiently for the passage of the head 18 therethrough, and after assembly of the two parts these separated walls are flattened out preventing disconnection of the two elements.

In operation, the tool can be applied and used with one hand. The jaws are opened up and the face 15 applied to the nut or other body and then the other jaw member slid through slot 12 until its surface 19 engages the opposite face of the nut and the jaw as a whole is in register with the other jaw, such engagement automatically bringing the edge 22 into contact with the wall 21, thereby providing a suitable and properly-positioned fulcrum for the work to be done. Then by pressing or squeezing the two handles toward one another by the hand which grasps them, the nut is firmly and securely held and may be turned or rotated with ease and facility.

In case it is desired to grip or turn nuts larger than can be easily accommodated between the two jaws directly in the manner specified, the pipe-wrench portion of the tool may be applied to the nut which gives an effective and non-slipping hold on such body and such an employment of the pipe-wrench part of the appliance increases the capacity or range of work of the tool.

In some cases it is desirable not only to guide the jaw end 18 of the lever or operating element 11, but also to give it a sliding bearing on the complementary lever to assist in securing and maintaining the most effective hold on the body to be manipulated whether it is held between the jaw faces 15 and 19 or grasped by the roughened curved pipe-wrench sections 16 and 20. Accordingly the edge 24 of the member 10 is so shaped that the part 23 of the thickened 45 jaw portion of the companion member may

bear thereon and slide along it to shift the jaw face 19 or the pipe-wrench part 20 into engagement with the work. Under these circumstances, the face 19 will travel toward the opposed jaw-face, always parallel thereto, the parts 21, 22 and 23, 24 maintaining their sliding engagement. When, therefore, the jaws are grasping a nut or similar body or a pipe the parts 21 and 22 and 23 and 24 will be bearing upon one another and the body will be held firmly and securely.

It is to be understood that this invention is susceptible of a considerable number of incorporations in physical form varying widely in their structural characteristics but all embodying the main and underlying principles of the invention. Consequently, it will be appreciated that the invention is not limited and restricted to the precise and exact features of construction illustrated and described, because these may be varied or changed within comparatively wide limits without departure from the substance and essence of the invention and without sacrificing any of its substantial benefits and advantages.

I claim:

A tool of the character described comprising in combination two handle elements provided at their corresponding ends with co-operating work-clamping jaws, one of said elements having a transverse slot therethrough slidably accommodating the other handle element, the latter having a smooth curved edge to provide a sliding adjustable fulcrum bearing on the end wall of said slot remote from said clamping jaws and having a portion adjacent to its jaw adapted to bear adjustably on an edge of said companion handle element, whereby when the jaws clamp a body between them both of said bearings of said handle element on the companion handle element will be operative, substantially as described.

ALLEN C. ALLAN.
